[57] CLAIM

The ornamental design for swimming pool floating dispenser, as shown and described.

DESCRIPTION

FIG. 1 is an elevational view taken from one side of a swimming pool floating dispenser showing my new design, the opposite side being a mirror image of the side shown;

FIG. 2 is a top plan view thereof;

FIG. 3 is a bottom plan view thereof;

FIG. 4 is a front elevational view thereof; and

FIG. 5 is a rear elevational view thereof.

Fig. 1.
